UNITED STATES PATENT OFFICE.

JOHN MANKOS, OF PALMERTON, PENNSYLVANIA.

WHIRLING TOY.

1,217,037.

Specification of Letters Patent. Patented Feb. 20, 1917.

Application filed September 2, 1916. Serial No. 118,262.

To all whom it may concern:

Be it known that I, JOHN MANKOS, a subject of the King of Hungary, residing at Palmerton, in the county of Carbon and State of Pennsylvania, have invented certain new and useful Improvements in Whirling Toys, of which the following is a specification.

This invention relates to certain new and useful improvements in whirling toys.

The primary object of the invention is the provision of a toy adapted to be held in the hand and operated for imparting a whirling movement to a portion thereof, a fanciful member being also given a vertical movement simultaneously with the operation of the device.

A further object of the invention is the provision of an anti-frictionally mounted member readily revolved alternately in opposite directions, the same having means for holding the same vertically positioned and with a vertically reciprocating ornamental figure.

With these general objects in view and others that will appear as the nature of the invention is better understood, the same consists in the novel construction, combination and arrangement of parts hereinafter more fully described, illustrated in the accompanying drawings, and then claimed.

In the drawings forming a part of this application and in which like designating characters refer to corresponding parts throughout the several views:—

Figure 1 is a central longitudinal sectional view through the device, portions being shown in side elevation, and,

Figs. 2, 3 and 4 are transverse sectional views taken respectively upon lines II—II, III—III and IV—IV of Fig. 1.

The present device being designed as a toy supported by one hand and operated by the other, the same broadly consists of a mount 10 having a shaft 11 journaled therethrough, the latter being provided at its lower end with an adjustable weight 12, an ornamental figure 13 being arranged upon the upper end of the said shaft and a pull cord 14 being carried substantially centrally by the shaft for operating the same rotarily.

The mount 10 consists of a handle 15 adapted to be grasped in one hand of the operator and with an ovoidal-shaped head 16 having a central chamber 17 therein, the

shaft 11 being journaled through the said head and chamber. An annular shoulder 18 is provided upon the shaft 11 at a point above the head 16 having suitable anti-friction members 19 positioned upon the flattened portion 20 at the upper side of the head whereby the shaft 11 is anti-frictionally journaled thereon.

The pull cord 14 is wound around the shaft 11 within the chamber 17 and has its inner end secured to the shaft as at 21 while the outer end of the cord is provided with a ring 22 adapted to be grasped for pulling the cord outwardly of the chamber 17 through the side perforation 23 of the head.

The weight 12 is of elongated form having a central chamber 24 therein and is slidably arranged upon the lower end of the shaft 11 being retained at the desired adjustment by means of a set screw 25. The weight 12 is preferably provided with a quantity of mercury 26 within the chamber 24 positioned in an annular space therein provided by means of a central block 27. The weight 12 is also provided with a plurality of transverse openings 28 adapted for giving a whistling sound to the toy, when the shaft and weight are rapidly revolved in either direction.

The aforementioned ornamental member 13 is here illustrated in the form of a bird and is mounted upon the upper closed end of a tube 29 freely positioned over the upper end of the shaft 11. A transverse bar 30 is carried adjacent the upper end of the said shaft provided with rollers 31 upon its opposite ends operatively arranged within spiral slots or guides 32 upon the inner face of the said tube. A washer 33 is secured to the lower end of the tube 29 having the shaft 11 freely journaled therethrough.

The complete operation of the device will be apparent from this detailed description thereof, it being understood that when the mount 10 is supported by means of the handle 15 in one hand of the operator, the ring 22 is grasped by the other hand being employed for violently pulling the cord 14 outwardly through the perforation 23, thereby revolving the shaft 11 in one direction whereupon a relaxing of the cord rewinds the same upon the shaft 11 within the head chamber 17 in an opposite direction from its original arrangement. Succeeding pulls upon the cord 14 by means of the ring 22 result in alternately revolving the shaft 11

in opposite directions. The position of the weight 12 upon the lower depending end of the shaft 11 will insure the shaft being held in true vertical position, it being also noted that the openings 28 provide a means for making a whistling sound during the operation of the device. The revolving of the upper end of the shaft 11 within the tube 29 forcibly revolves the bar 30 whereby the tube 29 moves upwardly upon the bar rollers 31 while at a cessation of the movement of the shaft 11 the tube 29 descends of its own weight to its normal position, being again elevated together with the bird 13 upon the next turning of the shaft 11 in the opposite direction. The ball bearings 19 arrange the shaft 11 for easy movement and a toy is provided which is easily operable and gives a pleasing appearance in the vertical reciprocating movements of the bird 13.

What I claim as new is:—

1. A toy comprising a mount, a shaft adapted for vertical positioning journaled through the said mount, revolving means for the said shaft, means for insuring the vertical position of the shaft, an ornamental figure, and a supporting tube for the said figure reciprocatingly mounted upon said shaft.
2. A toy comprising a mount having a head with a chamber therein, and a side perforation communicating with the said chamber, a shaft transversely journaled through the said head and extending through the said chamber, an operating cord extending through the said perforation and operatively attached to the said shaft within the said chamber, an annular shoulder upon the said shaft above the said head, anti-friction members between the said shoulder and head, a speed regulator adjustably mounted upon one end of the said shaft, and an ornamental member mounted for longitudinal movement upon its opposite end.
3. A toy comprising a mount having a head with a chamber therein, and a side perforation communicating with the said chamber, a shaft transversely journaled through the said head and extending through the said chamber, an operating cord extending through the said perforation and operatively attached to the said shaft within the said chamber, an annular shoulder upon the said shaft above the said head, anti-friction members between the said shoulder and head, an elongated weight having a chamber therein longitudinally adjustably arranged upon the lower end of the said shaft and having air openings there-through, a centrally arranged block within the said weight chamber, mercury arranged within the said chamber surrounding the said block, a transverse bar carried by the other end of the said shaft, rollers upon the opposite ends of the said bar, a tube freely mounted upon the said shaft provided with spiral grooves upon its inner surface within which the said rollers are positioned, and an ornamental figure carried by the said tube.

justably arranged upon the lower end of the said shaft and having air openings there-through, a centrally arranged block within the said weight chamber, mercury arranged within the said chamber surrounding the said block, and an ornamental figure reciprocatingly mounted upon the other end of the said shaft.

4. A toy comprising a mount having a head with a chamber therein, and a side perforation communicating with the said chamber, a shaft transversely journaled through the said head and extending through the said chamber, an operating cord extending through the said perforation and operatively attached to the said shaft within the said chamber, an annular shoulder upon the said shaft above the said head, anti-friction members between the said shoulder and head, a weight upon one end of the said shaft, a transverse bar carried by the other end of the said shaft, rollers upon the opposite ends of the said bar, a tube freely mounted upon the said shaft provided with spiral grooves upon its inner surface within which the said rollers are positioned, and an ornamental figure carried by the said tube.

5. A toy comprising a mount having a head with a chamber therein, and a side perforation communicating with the said chamber, a shaft transversely journaled through the said head and extending through the said chamber, an operating cord extending through the said perforation and operatively attached to the said shaft within the said chamber, an annular shoulder upon the said shaft above the said head, anti-friction members between the said shoulder and head, an elongated weight having a chamber therein longitudinally adjustably arranged upon the lower end of the said shaft and having air openings there-through, a centrally arranged block within the said weight chamber, mercury arranged within the said chamber surrounding the said block, a transverse bar carried by the other end of the said shaft, rollers upon the opposite ends of the said bar, a tube freely mounted upon the said shaft provided with spiral grooves upon its inner surface within which the said rollers are positioned, and an ornamental figure carried by the said tube.

In testimony whereof I affix my signature.

JOHN MANKOS.
